WILLIAM H. LIEBER, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

TRIMMER-SAW.

1,116,301.

Specification of Letters Patent.

Patented Nov. 3, 1914.

Application filed February 17, 1913. Serial No. 749,539.

To all whom it may concern:

Be it known that I, WILLIAM H. LIEBER, a citizen of the United States, residing at Milwaukee, in the county of Milwaukee and

5 State of Wisconsin, have invented a certain new and useful Improvement in Trimmer-Saws, of which the following is a specification.

This invention relates to improvements 10 in the construction of saw mill machinery, and particularly to improvements in apparatus for controlling the positions of a plurality of trimmer saws or similar devices.

15 An object of the invention is to provide a device for permitting either independent, selective or collective, positioning of a plurality of trimmer saws or similar devices, which is simple in construction and efficient 20 in operation.

Some of the features disclosed but not claimed herein are claimed in application S. N. 736,843.

25 Some of the more specific objects of the invention may be enumerated as follows:

To provide a device for permitting either individual, selective or collective control of the positions of a plurality of saws irrespective of the positions of prior setting 30 of the individual saws at the time such actuation is desired.

To provide means for permitting simultaneous collective positioning of all the saws either into or out of cutting position.

35 To provide means for automatically returning the master actuating means to a predetermined or mid position after either a selective or collective actuation of the saws has been made.

40 To provide an actuating mechanism in which the individual levers are similar in construction, thus making them interchangeable with each other and reducing the number of different parts to a minimum.

45 To provide a fluid pressure actuated means for positioning trimmer saws, in which the amount of fluid utilized is reduced to a minimum.

To provide means whereby upon failure 50 of the fluid pressure in the supply line, the saws will automatically move and remain out of cutting position. This feature is important as it eliminates the undesirable dropping of saws when the pressure fails.

55 In prior devices using retaining hooks, and

in which all saws not hooked at the time of pressure failure move into cutting position, the saws must be manually raised and hooked after pressure failure.

To provide means for automatically re- 60 turning the controlling mechanism of the saw positioning means to saws up position when the fluid supply fails.

To provide an actuating means for the saw positioning controlling mechanism in 65 which a single flexible connection may be employed to control the admission of fluid under pressure to each of the individual saw positioning means.

To provide a fluid admission means for 70 each of the saw positioning means, which is simple and durable in construction and efficient in operation.

To provide an effective means for cushioning the saw positioning means. 75

A clear conception of an embodiment of the invention may be had by referring to the drawings accompanying and forming a part of this specification in which like reference characters designate the same or 80 similar parts in the various views.

Figure 1 is a transverse vertical section through a trimmer saw control actuating device with the collective and selective actuating means in mid position. Fig. 2 is an 85 end view of a trimmer saw position control actuating device showing the collective actuating means in saws up position. Fig. 3 is an end view of a trimmer saw position control actuating device showing the collective actuating means in saws down position. Fig. 4 is a transverse vertical section through a trimmer saw position control actuating device showing the selective actuating means in operation. Fig. 5 is a front 95 view of a fragment of the trimmer saw position control actuating device, partly in section. Fig. 6 is an end elevation showing the general arrangement of the trimmer saws and positioning mechanism therefor. 100 Fig. 7 is a plan view showing the general arrangement of the saw positioning mechanism. Fig. 8 is a transverse vertical section through one of the individual saw position control mechanisms. Fig. 9 is an enlarged 105 transverse vertical section through one of the individual saw position controlling valves, showing same attached to a fragment of a saw positioning cylinder. Fig. 10 is a transverse horizontal section through 110

one of the individual saw position controlling valves, the section being taken along the line X—X of Fig. 9.

In the device disclosed in the drawings, 5 the saws are brought into cutting position by means actuated by fluid pressure to lower same and are thrown out of cutting position by spring means acting to raise same. For the purpose of explanation the positions 10 corresponding to into and out of cutting positions will be designated as "saws down" and "saws up" position, respectively. It should be understood, however, that these terms are correct only when applied to an 15 overhead trimmer and it is not intended to limit the application of this invention to that type of trimmer by the use of these terms. The term "collective" as used in the 20 present specification designates the simultaneous operation of all saws controllable by the mechanism. The term "selective" designates a predetermined allotment or portion of the total number of saws commonly known as the slasher saws. The "collective" 25 saws therefore include the selective or slasher saws as well as the intermediate or non-slasher saws.

The ordinary trimmer saw equipment generally includes a lumber conveying table 62, 30 upon which the material to be trimmed is automatically fed to the saws 56 by means of suitable conveying mechanism, see Fig. 6. The individual saws 56 are supported upon arms 57 which swing about pivots 64. A 35 common driving shaft 60 carries a series of driving pulleys 59 which are drivingly connected to the saw pulleys 61 by means of belts 58. The location of the pivots 64 of the arms 57 is such that with the saws 56 in 40 saws down position, the belts 58 are taut, and with the saws 56 in saws up position, the belts 58 are flexed.

The individual saw positioning means disclosed as cylinders 51, see Figs. 6 and 8, are 45 fixed to a beam 65 above the saws 56 by means of cap screws 95. A piston 96 is reciprocable within each of the cylinders 51 and is capable of imparting motion to its respective saw 56 through a piston rod 54 50 and an adjustable connection 55, the former of which is guided in a suitable bearing 102 formed in the cylinder 51. A cup leather packing 98 is secured to the piston 96 by means of a nut and follower 100, contact between the packing and the working surface 55 of the cylinder 51 being maintained by the use of an expander ring 99. A helical compression spring 97 coacts with its lower end against a surface of the cylinder 51, and 60 with its upper end against a lower surface of the piston 96. This spring 97 tends at all times to force the piston 96 and its respective saw 56 into saws up position. The vent 101 permits escape of air from the 65 spring chamber below the piston 96.

The upper end of the cylinder 51 is provided with a common admission and exhaust port 72 which penetrates the cylinder wall some distance below the end thereof, see Figs. 8, 9 and 10.

The means for cushioning the piston 96 at the upper end of its stroke consists of a hole 69, preferably drilled into the end of the cylinder 51 and connecting with the port 72 through a smaller drilled hole 81. The hole 70 69 connects with the extreme end of the interior of the cylinder 51 through a transversely formed slot or hole 90. The ends of the cylinder 51 and hole 69 are inclosed by means of a plate 92 which is clamped between the cylinder 51 and the beam 65 to prevent leakage of working fluid from within the cylinder 51. The non-return check valve 70 permits the free passage of fluid from the port 72 through the holes 81, 69, 90, 85 to the interior of the cylinder 51, but does not permit the return of fluid from the cylinder 51 to the port 72 through these holes.

The saw position controlling valve boxes 52 are secured to their respective cylinders 51 by means of studs 73, see Fig. 10. Each of the boxes 52 has annular admission and exhaust chambers 68, 86, formed substantially concentric with their respective admission and exhaust valve pistons 76, 78. 95 The admission valve piston 76 carries a puppet valve 84, which preferably consists of a removable leather disk. The exhaust valve piston 78 carries a similar puppet valve 85. The admission and exhaust valve pistons 76, 78, are rigidly but removably connected by means of a valve stem 75. The admission valve piston 76 controls the admission ports 66, which are directed from the chamber 68 toward the puppet valve controlled admission port 71, and are so spaced around the valve piston 76 that the pressure of the fluid admitted through the port 66 will be substantially balanced in its effect upon the valve, around the entire periphery 110 thereof. The exhaust valve piston 78 controls the exhaust ports 87 which are directed from the puppet valve controlled exhaust port 91 toward the chamber 86, and are uniformly spaced around the piston 78. The valve seats 74, 94, of the puppet valves 84, 85, are formed as annular ridges and surround their respective admission and exhaust ports 71, 91. The ports 71, 91, connect with the common chamber 80 which communicates with the interior of the saw positioning cylinder 51 through the port 72. The annular recess 89 formed adjacent to the seat 94, is constantly in communication with the exhaust chamber 86, through a small drilled port 88. The fluid pressure supply header or pipe 53 is connected with the individual admission chambers 68 of the boxes 52 by means of nipples 67. The individual exhaust chambers 130

86 of the boxes 52, communicate with the atmosphere through ports 82. The combined piston and puppet valve is preferably vertically disposed and is provided with a 5 spring seat 79 at one of its ends. The helical compression spring 83 coacts between the seat 79 of the valve and the valve box 52, and normally tends to retain the valve in its lower or sows up position. The upper 10 extremity of the combined piston and puppet valve is provided with an I-bolt 77, which forms means for connecting the valve with its corresponding flexible connection 19 leading to the actuating means.

15 The saw controlling valve actuating device consists of a series of selective or slasher saw levers 12, and a series of similar but reversely arranged intermediate saw levers 13, see Figs. 1 to 5. The levers 12, 13, are 20 connected with the controlling valves of their respective saws 56 by means of the flexible connections 19 which pass through and are secured to the levers 12, 13 by means of slack adjustment permitting means or 25 nuts 29. The connections 19 are guided to permit proper and free actuation of their respective valves by means of guide wheels or pulleys 20, 63. The pulleys 63 are mounted upon suitable brackets 93 which are secured 30 to the beam 65. The pulleys 20 are mounted in suitable brackets which are angularly adjustably secured to the base plate 17 by means of swivels 23. The flexible connections 19 are led in any convenient manner 35 from the controlling valves to their respective levers 12, 13, which are stationed in the operating cage 50 of the mill.

The levers 12, 13 are mounted upon a common shaft 14, which is supported in 40 end bearings 16, 33, secured to the base plate 17 by means of cap screws 42. The upper ends of the levers 12, 13, are provided with finger grips below which the designating numerals of the saws are preferably 45 placed. The selective saw levers 12 are provided with projecting fins 120, which extend away from the operator, while the corresponding similar fins 130 of the intermediate levers 13 extend toward the operator.

50 The levers 12, 13 have downwardly extending projections 21, 31, respectively, which, with the levers 12, 13, in saws down position, coact in recesses formed in the leaf springs 22. The levers 12, 13 are identical 55 in structure and differ only in their relative mounting with respect to the shaft 14. With the levers 12, 13, in saws down position, the leaf springs 22 tend to retain them in such position with a holding effect which 60 is somewhat less than the normal pull exerted upon the levers 12, 13, by the springs 83 through the valves and flexible connections 19.

65 The master actuating device consists of a pair of master clutch levers 11 which are mounted to swing upon the shaft 14. These clutch levers 11 are automatically returned to the predetermined or mid position upon release of same by the operator, by means of springs 15, the ends 35, 36 of which normally coact with adjacent surfaces formed on corresponding sides of lugs 34, 37, projecting from the levers 11 and bearings 33, respectively. If the levers 11 are moved in a clockwise direction, see Fig. 2, the 70 spring ends 35 tend to return them to mid-position by exerting pressure against the projections 34. As the levers 11 are moved in an anticlockwise direction, see Fig. 3, the spring ends 36 tend to return them to mid-position by exerting pressure against the projections 34.

The clutch mechanisms of the levers 11 consist of wedge blocks 26, 38, carried by the lower ends of the rods 40, the upper 85 ends of which carry actuating plungers 27. The plungers 27 are normally retained in their uppermost position by means of helical compression springs 41 which are enclosed within the handles of the levers 11. 90 The wedges 26 of the wedge blocks normally coact with recesses 46 formed in the collective control actuating arms 24. With the plungers 27 forced into their extreme lowest positions as disclosed in Fig. 4, the 95 wedges 38 of the wedge blocks are forced out of engagement with the recesses 46 and into coaction with the recesses 28 of the slasher or collective control actuating arms 25.

The collective control actuating arms 24 are connected by means of cross rods 9, 10, which are capable of being swung about the axis of the shaft 14 along a cylindrical surface which lies beyond the upper ends of 105 the fins 120, 130. The selective control actuating arms 25 are connected directly by means of the cross rod 8 and indirectly by means of the cross rod 7. The levers 6 are pivoted to swing upon stationary pivots 30, 110 which are fixed to the bearings 16. The upper ends of the levers 6 are connected by means of the cross rod 7, while the lower ends thereof are slotted to receive the wearing blocks 39. The blocks 39 are pivotally mounted upon pins 32 secured to the arms 25.

115 During the normal operation of the device and at such times when the collective and selective positioning of the saws 56 is not desired, the master actuating device is in the position shown in Fig. 1 and actuation of the individual levers 12, 13 is unrestricted by the cross rods 7, 8, 9, 10. With the mechanism thus positioned, any one or more of 120 the individual saws 56 may be brought into cutting or saws down position by pulling its corresponding lever 12, 13, toward the operator. A pull on one of the levers 12, 13, acts through its corresponding connection 130

19 to raise the combined piston and puppet valve 76, 78, 84, 85, connected therewith, positioning the valve as indicated in Fig. 9 and compressing spring 83. Fluid under pressure is then free to pass from the supply header 53 through the inlet pipe 67, chamber 68, ports 66, 71, chamber 80 and ports 72, 81, 69, to the interior of the saw positioning cylinder 51. The admission of air under pressure to the chamber above the piston 96, forces the piston and its corresponding saw 56, toward the table 62 and into cutting position, against the action of the spring 97, which is meanwhile compressed.

16 With the controlling valve in the position indicated in Fig. 9, the area of the puppet valve 84 which is exposed to fluid pressure is considerably greater than the corresponding pressure exposed area of the puppet valve 85. Assuming the difference in pressure upon these pressure exposed surfaces of the puppet valves to be 20 pounds, and that the spring 83 exerts a downward pressure of 25 pounds, it will then be necessary for the leaf spring 22 of the corresponding saw actuating lever 12, 13, to exert a lever locking or holding pressure which is in excess of the difference between 25 the unbalanced fluid pressure on the valve and the pressure exerted by the spring 83. For convenience it may be assumed that the lever locking pressure is 10 pounds, in which case the excess or actual unbalanced 30 holding effect of the spring 22 upon the lever 12, 13 while in saws down position, will be 5 pounds. The above figures are assumed merely for purposes of description and it is not intended to limit the invention 35 to any figures assumed for such purpose.

If it is desired to raise the saw 56 out of cutting position, it is necessary to move the lever 12, 13 of the saw 56 which it is desired to position, in a clockwise direction, 40 thus breaking the lock between the end of the lever 12, 13, and the spring 22. This release of the locking pressure of the spring 22 immediately permits the valve spring 83 to become effective in automatically lowering or closing the valve. The automatic closing of the valve is accomplished by the excess of 5 pounds downward pressure exerted by the spring 83, above the 20 pounds unbalanced fluid pressure upon the puppet 45 valves 84, 85. As the combined piston and puppet valve 86, 84, moves downwardly, it closes off the fluid pressure supply through the ports 66. Simultaneously with the closing off of the fluid pressure supply, the 50 combined piston and puppet valve 78, 85, permits the escape of fluid from within the positioning cylinder 51 to the atmosphere through the exhaust ports 87. Upon release of the fluid pressure from above the 55 piston 96, the spring 97 becomes effective

in raising the piston and its corresponding saw 56 to saws up position. When the piston 96 in its upward travel passes the port 72, it confines air in the cylinder chamber above the port 72, thus forming an effective cushion for the upper end of the piston stroke. The piston 96 should not be permitted to travel beyond the port 72 so as to establish communication between the port 72 and the chamber below the piston, since such a communication would permit high pressure fluid to enter the chamber below the piston rather than to pass through the check valve 70 to the upper piston chamber. Since the upward pressure exerted by the spring 97 increases as the piston 96 is lowered, the desired cushioning effect for the lower end of the piston 96 will be produced by the spring itself.

If it is desired to manually operate the saws 56 collectively to raise same, this may be done by moving one of the master actuating levers 11 into the position shown in Fig. 2. Upon movement of a master lever 11 in a clockwise direction, the plunger 27 thereof remaining undisturbed, the wedge 26 thereof engages the recess 46 of the corresponding arm 24, causing the arm to move in a clockwise direction. Such movement of the arm 24 causes the cross rod 10 to engage all of the individual levers 12, 13, which are not in saws up position, and to move these levers into saws up position. Upon release of the lever 11 by the operator, the springs 15 automatically return the levers 11 and arms 24 to mid position.

If it is desired to operate the saws 56 collectively to lower same, this may be done by moving a master actuating lever 11 into the position shown in Fig. 3. Upon movement of a master lever 11 in an anti-clockwise direction, the plunger 27 thereof remaining undisturbed, the wedge 26 thereof engages the recess 46 of the corresponding arm 24, causing the arm 24 to move in an anti-clockwise direction. Such movement of the arm 24 causes the cross rod 9 to engage all of the individual levers 12, 13, which are not in saws down position, and to move these levers into saws down position. Upon release of the lever 11 by the operator, the springs 15 automatically return the levers 11 and arms 24 to mid position. The collective lowering of the saws may be desirable when the material is to be cut into short uniform lengths equal to the distance between successive saws.

If it is desired to operate the selective or slasher saws 56 as in cutting lath lengths, it is necessary first to press the plunger 27 of one of the master actuating levers 11 downward by use of the thumb, and with the plunger 27 in such position, to move the lever 11 to the position indicated in Fig. 4. During the downward pressing of the

plunger 27, the wedge 26 is withdrawn from the recess 46, and the wedge 38 is simultaneously brought into engagement with the recess 28. With the wedge 38 thus positioned, anti-clockwise movement of its lever 11 will cause the arms 25 to move, carrying with them the cross rod 8. The cross rod 8 during its anti-clockwise movement automatically engages the fins 120 of the slasher levers 12 which are not in saws down position, and places these levers into saws down position. Simultaneously with the movement of the arms 25 in an anti-clockwise direction, the levers 6 are swung about the pivots 30 by means of the pins 32 and blocks 39 which coact with the slots at the lower ends of the levers 6. The movement of the cross rod 7 connecting the upper ends of the levers 6 resulting from the motion imparted to the levers 6 by the arms 25, is clockwise and causes the rod 7 to engage all of the fins 130 of the intermediate levers 13 which are not in saws up position, and to place these levers into saws up position. Upon release of the lever 11 by the operator, the springs 15 automatically return the levers 11 and arm 24 to mid position, after which the wedges 26 are automatically snapped into engagement with the recesses 46. Disengagement of the wedges 38 before the levers 11 reach the mid position, is prevented by suitable guides formed on the arms 24. The arms 24 during selective setting of the saws 56 are prevented from moving by the coaction of the rod 10 with the locked levers 12.

It should be noted that by reversing the respective positions of the levers 12, 13, upon the shaft 14, the saws 56 may readily be transformed to operate as slasher or intermediate saws from prior operations as intermediate or slasher saws, respectively. It should also be observed that the levers 12, 13 are exactly alike and that the various other elements of the device are also duplicated as much as possible in order to facilitate the furnishing of repair parts.

If for any reason the pressure in the supply header 53 should fail, either temporarily or permanently, as in closing down the mill at night, the unbalanced pressure of 20 pounds on the puppet valves 84, 85, of those saws which are in cutting position at the time, will be automatically destroyed and the total pressure of 23 pounds of the springs 83 corresponding to such saws, will immediately become effective in releasing the corresponding individual levers 12, 13, and in opening the corresponding controlling valves to exhaust. This automatic action of the springs 83, places all of the saws 56 into saws up position, and at the same time closes off the pressure inlet ports 66 and returns the individual levers 12, 13, to saws up position. The advantage of this

arrangement is that upon reestablishment of the fluid pressure within the header 53, the saws 56 will remain in saws up position until otherwise positioned by the operator.

The location of the supply header 53 as near to the positioning cylinders 51 as possible, assures very quick action of the device and reduces the amount of fluid under pressure necessary to position the saws to a minimum. The use of mechanical means for raising the saws, eliminates the necessity of providing means, such as a hook, for keeping the saws 56 out of cutting position in order to keep the belts flexed. Such construction furthermore requires the admission of fluid under pressure to the positioning cylinders 51 only during the time that the corresponding saws 56 thereof are in cutting position. As the relative time during which the saws 56 are in cutting position is considerably less than that in which they are out of cutting position, this feature of the present invention assists in reducing the amount of fluid under pressure required to operate the device, to a minimum.

The use of but a single flexible connection 19 for connecting each of the individual actuating devices with its respective controlling valve, simplifies the construction and prevents unnecessary obstruction of the operator's view of the various saws 56.

It should be understood that it is not desired to be limited to the exact details of construction shown and described, for obvious modifications will occur to a person skilled in the art.

It is claimed and desired to secure by Letters Patent,—

1. In combination with a table, a plurality of saws movable into and out of cutting position relative to said table, actuating means for effecting selective setting of said saws, and means for returning said actuating means to a predetermined position.

2. In combination with a table, a plurality of saws movable into and out of cutting position relative to said table, actuating means for effecting collective setting of said saws, and means for returning said actuating means to a predetermined position.

3. In combination with a table, a plurality of saws movable into and out of cutting position relative to said table, individual means for normally setting each of said saws in either of said two positions, actuating means for effecting selective setting of said saws, and means for returning said actuating means to a predetermined position.

4. In combination with a table, a plurality of saws movable into and out of cutting position relative to said table, individual means for normally setting each of said saws in either of said two positions, common actuating means for effecting collective and selective setting of said saws, and means for

returning said actuating means to a predetermined position.

5. In combination with a table, a plurality of saws movable into and out of cutting position relative to said table, individual levers for normally setting each of said saws into either of said two positions, a master lever for effecting collective or selective setting of said saws, and means for automatically 10 returning said master lever to mid position.

6. In combination with a table, a plurality of saws movable into and out of cutting position relative to said table, actuating means for effecting either collective or selective setting of said saws, and means for returning said actuating means to a predetermined position.

7. In combination with a table, a plurality of saws movable into and out of cutting position relative to said table, fluid pressure actuated means for moving said saws into cutting position, controlling means for said fluid pressure actuated means, and means for automatically returning said controlling 25 means to a predetermined position upon failure of the actuating fluid pressure.

8. In combination with a table, a plurality of saws movable into and out of cutting position relative to said table, fluid pressure 30 actuated means for moving said saws into cutting position, controlling means for said fluid pressure actuated means, means for automatically returning said controlling means to a predetermined position upon 35 failure of the actuating fluid pressure, and mechanical means for moving said saws out of cutting position.

9. In combination with a table, a saw 40 movable into and out of cutting position relative to said table, fluid pressure actuated means for moving said saw into one of said two positions, controlling means for said fluid pressure actuated means, actuating means for said controlling means, a single 45 flexible connection for communicating motion from said actuating to said controlling means, and means acting through said connection for returning said controlling means to a predetermined position upon release of 50 said actuating means.

10. In combination with a table, a saw 55 movable into and out of cutting position relative to said table, fluid pressure actuated means for moving said saw into one of said two positions, a combined piston and puppet valve for controlling said fluid pressure actuated means, means tending automatically to force said valve in one direction and to move said saws out of cutting position, and 60 means for moving said valve in the opposite direction whereby said saws are moved into cutting position.

11. In combination with a table, a saw 65 movable into and out of cutting position relative to said table, fluid pressure actu-

ated means for moving said saw into one of said two positions, a combined piston and puppet valve for controlling said fluid pressure actuated means, means normally tending to maintain said valve open to exhaust, 70 and means acting in conjunction with unbalanced fluid pressures on said valve for maintaining said valve open to pressure.

12. In combination with a table, a plurality of saws movable into and out of cutting position relative to said table, fluid pressure actuated means for moving said saws into cutting position, spring means for moving said saws out of cutting position, and means for cushioning said saw moving 80 means.

13. In combination with a table, a saw 85 movable into and out of cutting position relative to said table, fluid pressure actuated means for moving said saw into one of said two positions, controlling means for said fluid pressure actuated means, actuating means for said controlling means, a single flexible connection for communicating motion from said actuating to said controlling 90 means, and means for moving said controlling means to a position to which corresponds out of cutting position of said saw, when the end of said flexible connection adjacent said actuating means is moved toward said controlling means.

14. In combination with a table, a saw 95 movable into and out of cutting position relative to said table, fluid pressure actuated means for moving said saw into one of 100 said two positions, controlling means for said fluid pressure actuated means, actuating means for said controlling means, and a single flexible connection for communicating motion from said actuating to said controlling means, said controlling means being movable for maintaining said flexible connection taut and for returning said controlling means to a predetermined position upon release of said actuating means.

15. In combination with a table, a saw 105 movable into and out of cutting position relative to said table, fluid pressure actuated means for moving said saw into one of said two positions, controlling means for 110 said fluid pressure actuated means, actuating means for said controlling means, a single flexible connection for communicating motion from said actuating to said controlling means, and means for maintaining 115 said flexible connection taut at all times said means tending to return said actuating means to a predetermined position.

16. In combination with a table, a saw 120 movable into and out of cutting position relative to said table, fluid pressure actuated means for moving said saw into one of said two positions, controlling means for 125 said fluid pressure actuated means, automatic means tending at all times to move 130

said controlling means in a position to which corresponds out of cutting position of said saw, and actuating means for said controlling means.

5 17. In combination with a table, a saw movable into and out of cutting position relative to said table, fluid pressure actuated means for moving said saw into one of said two positions, controlling means for

10 said fluid pressure actuated means, means tending to maintain said controlling means in a position to which corresponds out of cutting position of said saw, actuating means for said controlling means, and a 15 single flexible connection for communicating motion from said actuating to said controlling means.

18. In combination with a table, a plurality of saws movable into and out of cutting position relative to said table, actuating means for effecting setting of at least one of said saws into either of said two positions, and means for automatically returning said actuating means to a predetermined position.

23 19. In combination with a table, a saw movable into and out of cutting position relative to said table, fluid pressure actu-

ated means for moving said saw into one of said two positions, controlling means for said fluid pressure actuated means, actuating means for said controlling means, and a single flexible connection for communicating motion from said actuating to said controlling means, said controlling means being automatically movable to maintain said flexible connection taut at all times.

20. In combination with a table, a saw movable into and out of cutting position relative to said table, fluid pressure actuated means for moving said saw into one of said two positions, a valve for controlling said fluid pressure actuated means, means tending automatically to move said valve in a direction to which corresponds out of cutting position of said saw, and means for moving said valve in a direction to which corresponds into cutting position of said saw.

In testimony whereof, the signature of 50 the inventor is affixed hereto in the presence of two witnesses.

WILLIAM H. LIEBER.

Witnesses:

G. F. DE WEIN,
ROB. E. STOLL.
